Des. 208,093
Patented July 18, 1967

208,093

CARTRIDGE CONTAINING MAGNETIC TAPE

William P. Lear, Wichita, Kans., assignor to Lear Jet Corporation, Wichita, Kans., a corporation of Delaware

Filed Sept. 30, 1965, Ser. No. 87,228

Term of patent 14 years

(Cl. D26—14)

FIG. 1

FIG. 2

FIG. 3

FIG. 4

FIG. 5

FIG. 6

FIG. 1 is a top, rear and right side (as viewed from the rear) perspective view of a cartridge containing magnetic tape, showing my new design;

FIG. 2 is an elevational view of the cartridge as seen from the left (far) side of its showing in FIG. 1;

FIG. 3 is an elevational view, as seen from the right (near) side of its showing in FIG. 1;

FIG. 4 is a front end elevational view.

FIG. 5 is a plan view of the bottom of the cartridge.

FIG. 6 is a rear elevational view thereof.

I claim:

The ornamental design for cartridge containing magnetic tape, as shown,
